United States Patent Office.

WILLIAM P. CHASE, OF BOSTON, MASSACHUSETTS, ASSIGNOR TO R. HOE
AND COMPANY, OF NEW YORK CITY.

Letters Patent No. 77,958, dated May 19, 1868.

IMPROVEMENT IN BOOKBINDERS' BEVELLING-MACHINE.

The Schedule referred to in these Letters Patent and making part of the same.

TO ALL WHOM IT MAY CONCERN:

Be it known that I, WILLIAM P. CHASE, of the city of Boston, in the county of Suffolk, and State of Massachusetts, have invented certain new and useful Improvements in Machines for Bevelling Bookbinders' Boards, and similar articles; and I do hereby declare the following to be a full, clear, and exact description of the same, reference being made to the drawings accompanying this specification, and the figures and letters of reference thereon.

Figure 1 of the said drawings is a view in perspective of the machine.

Figure 2 is a top view.

Figure 3, a vertical sectional view of the same, taken through the line $z z'$.

Figure 4 is a perspective view of the plane.

Figure 5 is an under side view of the same, and

Figure 6 is a sectional view of the latter, through the line $y y'$.

Similar letters of reference indicate like parts in the several drawings.

My invention consists, first, in the employment of a reciprocating plane, provided with an oblique cutter, in combination with an oblique groove to guide the plane in its travel, whereby I am enabled to obtain a smooth shear-cut of the book-board or other material; second, in the combination of the adjustable plates, for holding the material for the action of the cutter, with the oblique groove and the reciprocating cutter; third, in the combination, with the oblique groove and reciprocating cutter, of the adjustable bed-plate, for giving any desired bevel to the edge of the material; fourth, in making the face of the plane concave, in combination with an oblique cutter; fifth, in the combination and arrangement of the oblique groove, the reciprocating oblique cutter, and the adjusting and holding-plates, all of which will be fully set forth.

To enable others skilled in the art to make and use my invention, I will describe its construction and mode of operation.

The side pieces A A, which support the bed of the machine, are made with two ears, d, by which the machine can be secured to a bench or table, and with two lugs, e, provided with holes for the set-screws E E. The adjustable plates B B are attached to the side pieces, in an inclined position; the lower plate being stationary, and the upper one adjustable, so that the aperture between them, through which the material projects, may be adjusted to different thicknesses of board. On these plates, and at an angle with the space between them, are placed the guides C C, which govern the movements of the plane H.

The bed-plate D, on which the material is laid, is placed beneath the plates B, and is capable of being adjusted at any desired angle, by means of the screws F F, passing through the slots a a, in the pieces A, and working in holes in the projections G, on the under side of the plate.

The plane H is made of the desired shape, with its face or under surface concave, to prevent abrasion of the material, and its cutting-iron is so placed at an angle with the aperture between the plates B B, that a sliding or shear-cut is made by the plane.

The machine is operated as follows: The space between the plates B B is adjusted to allow the material to project above their surface, by moving the upper plate to or away from the lower plate the necessary distance, and retaining it in place by turning the set-screws E E, and the bed-plate D is adjusted to the angle it is desired to give the bevel on the edge of the material.

The book-cover or other article being placed and held in position on the bed-plate, a clean and even bevel of its edge is obtained by reciprocating the plane in its groove.

Claims.

I claim—

1. The reciprocating plane, provided with an oblique cutter, in combination with the oblique groove, to

- guide the plane in its travel, whereby I am enabled to obtain a smooth shear-cut of the material, substantially as set forth and specified.
2. The combination, with the oblique groove and reciprocating cutter, of the adjustable plate B, for holding the material for the action of the cutter, substantially as set forth and specified.
3. The combination, with the oblique groove and reciprocating cutter H, of the adjustable bed D, for giving any desired bevel to the material, substantially as set forth and specified.
4. Making the face of the cutter or plane H concave, in combination with the oblique cutting-iron I, whereby I obtain a clean, smooth cut, without abrading the material, substantially as specified.
5. The combination and arrangement of the oblique guides C C, the reciprocating plane H, holding-plates B B, and adjusting-plate D, constructed and operating substantially as set forth and specified.

WILLIAM P. CHASE.
